UNITED STATES PATENT OFFICE.

EDWARD P. BARRETT AND JOHN A. FORSTER, OF HOLDEN, MISSOURI.

CLIP FOR NECK-YOKES, &c.

SPECIFICATION forming part of Letters Patent No. 299,901, dated June 3, 1884.

Application filed December 13, 1883. (No model.)

To all whom it may concern:

Be it known that we, EDWARD P. BARRETT and JOHN A. FORSTER, both of Holden, Johnson county, in the State of Missouri, have invented a certain new and useful Improvement 5 in Clips for Neck-Yokes, Single-Trees, &c., of which the following is a specification.

In order that the invention may be fully understood, we will proceed to describe it, with 10 reference to the accompanying drawings, in which—

Figure 1 is a perspective view showing part 15 of a neck-yoke having our improved clip applied thereto. Fig. 2 is a perspective view of a plate which is employed to form a bearing for the inturned ends of the clips. Fig. 3 is a perspective view of our improved clip. Fig. 4 is a section taken on line 4 4, Fig. 1; and Fig. 5 is a perspective view showing our im- 20 proved clip secured to a single-tree, only part of the single-tree being shown.

Our invention relates to a clip having turned-in ends for use on neck-yokes, single-trees, and like purposes.

25 Our invention consists in features of novelty hereinafter fully described, and pointed out in the claim.

Referring to the drawings, A represents the 30 middle or central part of a neck-yoke in Fig. 1, and the same part of a single-tree in Fig. 5.

B represents a plate secured to the upper edge of the neck-yoke in the one case, and to the back of the single-tree in the other.

C represents our improved clip, which is U-shaped. Its ends C' are turned inward, as 35 shown, and adapted to fit in notches B' of the plates B. The clip is also, preferably, provided with shoulders C², which fit against the front edges of the neck-yoke or single-tree. A neck-yoke is preferably provided with two 40 of these clips, as shown, the ring D being connected thereto by links D', while the single-tree requires but one, having a solid clevis, J.

Before attaching the clips to the neck-yoke or single-tree they are slipped through the 45 links or rings, (by means of the open ends,) and then they are slipped over the neck-yoke or single-tree, as the case may be, and brought into the proper position, where they are held by pins or rivets I, or by other suitable means. 50

We claim as our invention—

The combination of a block, A, U-shaped clip C, having shoulders C² and inturned ends C', and the plate B, having recesses B' to receive the clip ends, as set forth.

EDWARD P. BARRETT.
JOHN A. FORSTER.

In presence of—

GEO. H. KNIGHT,
SAM'L. KNIGHT.
